UNITED STATES PATENT OFFICE.

GIUSEPPE MAZZOLINI, OF NAPLES, ITALY.

DOOR, HATCH, OR LIKE CLOSING DEVICE.

1,029,620.

Specification of Letters Patent. Patented June 18, 1912.

Application filed February 6, 1909. Serial No. 476,554.

To all whom it may concern:

Be it known that I, GIUSEPPE MAZZOLINI, a subject of the King of Italy, residing at Naples, Italy, gentleman, have invented 5 certain new and useful Improvements in or Relating to Doors, Hatches, or Like Closing Devices, of which the following is a specification.

This invention relates to a device for the 10 opening and closing of sliding doors, bulkheads, etc., of ships, which are connected in such a way to their sliding mechanism that the door after being brought opposite the opening which is to be closed, can execute a 15 further movement, for the purpose of tightly pressing the door against its frame. This last movement is produced by wedges in a known manner.

The invention is distinguished from other 20 devices serving similar purposes, by the facts, that firstly the door during its entire sliding movement, is carried along by the frame, which is connected to the moving device by means of wedges in the frame 25 which drop into corresponding recesses in the door, and secondly that the wedges and the corresponding inclines on the door are built in such a manner that there takes place toward the end of the sliding movement 30 a sharp blowlike pressing of the door into its opening. To this end the invention provides on the inner side of the door as a continuation of the sharply inclined planes of the wedge recesses, other less sharply 35 inclined planes. Along these slide, with little resistance, the upper edges of the wedges, which, when the door is closed, protrude from their recesses and press thereby the door sharply in the opening. Thus is 40 guaranteed a safer and tighter closing of the door than in known similar devices.

A form of construction according to this invention is illustrated in the accompanying drawings in which—

45 Figure 1 is a view in rear elevation, the door being opened, part of the casing being broken away for the sake of clearness; Fig. 2 is a sectional view on the line A. B of Fig. 1; Fig. 3 is a view similar to Fig. 1 showing the door in a closed position; Fig. 4 is a sectional view of line C. D of Fig. 3; Fig. 5 is an elevational view of the sliding frame; Fig. 6 is a sectional view on the line C. F. of Fig. 5; Fig. 7 is a sectional view 50 on the line G. H. of Fig. 1; Fig. 8 is a sectional view on the line I. L. of Fig. 3; Fig. 9 is a sectional detail view of the wedge 9 and its coöperating parts; Fig. 10 is a sectional elevational view of the wedge 9 and its coöperating parts, parts being shown in 60 section for the sake of clearness.

The movement of door 2 is brought about by means of a piston rod 14 actuated in any suitable manner, and which is connected to frame 1, by clamps 12 which slide by means 65 of flanges on wedges 9 and 10. Frame 1 is slidingly supported upon suitable guides by means of a sliding member 23, and is connected to door 2 by a metal spring plate 3 provided with a slot 4 with which engages 70 a button 5 secured to the door, so that the frame may move relatively to the door a distance equal to the length of the slot 4.

To the frame are attached wedges 6 which engage correspondingly shaped recesses 8 75 formed in the door. The inclined surfaces of the recesses are inclined in the same manner as the corresponding surfaces of the wedges. Directly in line with the recesses 8 and closely adjacent the inclined surfaces 80 thereof are the wedges 7, the surfaces of which are inclined to a less extent than are the inclined surfaces of the recesses 8 to the wedges 6.

The door slides upon rollers or balls 16 in 85 the groove 22 which slope toward the door opening so as to bring the front edge of the door to the edge of the opening and said grooves are provided with slots 17 into 90 which the balls 16 enter when door is in its closed position.

The device acts as follows: In order to 95 close the door the piston rod 14 attached to frame is moved toward the left, as shown in Fig. 1, and the frame 1 moves the door 2 by means of the wedges 6 engaging within the recesses 8, until the door is brought opposite the opening at which point the further movement is arrested. In consequence of 100 slot and button connection 4 and 5 the piston 105 14 with the frame 1 and wedges 6 will move relatively to door a distance equal to the length of the slot 4, and during the movement of the frame the wedges 6 will slide along the recesses 8 forcing the door toward the opening. When the inclined surfaces of the wedges 6 protrude from the recesses, they engage the less inclined surfaces 110 of the wedges 7 of the door, slide quickly along them on account of the limited resistance, and firmly press the door into the opening and against the door frame. When

opening the door the process is reversed and at the first backward movement of the piston rod 14 the door will recede from the door frame as far as the wedges 7 allow, 5 since the door does not take part in the initial movement of the piston rod owing to the slot 4 and only begins to slide in the direction of its length after the wedges 6 have entered the recesses 8.

10 Instead of employing a piston rod to move the frame, any manually operated means may be used if desired, as for example a rack and pinion as shown in Fig. 3.

Having now particularly described and 15 ascertained the nature of my said invention and in what manner the same is to be performed, I declare that what I claim is:—

1. In apparatus of the class described, in combination, a frame provided with wedges, 20 said frame being directly connected to a driving motor, a sliding door movably connected to said frame, said door being provided with recesses and counter-wedges, the wedges on said frame being adapted to 25 enter said recesses, the inclined surfaces of the wedges on the frame being adapted to engage the inclined surfaces of the counter-wedges upon the door, means for moving said frame to bring the door in registry 30 with the opening, and means to arrest the movement of said door relatively to said frame to cause the inclined surfaces of the wedges of the frame to leave the recesses and slide along the inclined surfaces of the 35 counter-wedges on the door, whereby the door will be forced to move in a direction substantially at right angles to its first direction of movement.

2. In apparatus of the class described, in 40 combination, a frame provided with wedges, a sliding door movably connected to said frame, said door being provided with recesses and with associated counter-wedges, the angle of inclination of the inclined surfaces of said counter-wedges being less than 45 that of the inclined surfaces of the recesses, the wedges on the frame being adapted to enter into the recesses, the inclined surfaces of the wedges on the frame being adapted 50 to engage the inclined surfaces of the counter-wedges on the door, means to move the said frame to bring the door in registry with the opening, and means to arrest the movement of the door whereby the movement 55 of the frame relatively to the door

will produce a sliding of the inclined surfaces of the wedges along the inclined surfaces of the counter-wedges, thereby causing the door to move in a direction substantially at right angles to its first direction of 60 movement.

3. In apparatus of the class described, in combination, a door frame, a sliding door associated therewith and provided with recesses having inclined surfaces, a frame 65 movably connected to said door and provided with wedges adapted to enter said recesses, the inclined surfaces of the wedges being adapted to engage the inclined surfaces of the recesses, means for moving said frame to move said door into registry with the door frame and means for arresting the movement of the door, whereby movement of said frame relatively to said door, will cause the inclined surfaces of the wedges to 70 slide along the inclined surfaces of the recesses thereby forcing the door to move in a direction substantially at right angles to its 75 first direction of movement.

4. In apparatus of the class described, in 80 combination, a door frame, a sliding door associated therewith and provided with recesses having inclined surfaces, said door being provided with wedges in registry with said recesses and adjacent the inclined 85 surfaces thereof, the inclination of the surfaces of said wedges being less than the inclination of the surfaces of said recesses, a frame movably connected to said door and provided with wedges adapted to enter said recesses, the inclined surfaces of the wedges being adapted to engage the inclined surfaces of the recesses, means for moving said frame to move said door into registry with the door frame, and means for arresting the 90 movement of the door, whereby movement of said frame relatively to said door will cause the inclined surfaces of the wedges to slide along the inclined surfaces of the recesses and into engagement with the wedges 100 on said door, thereby forcing the door to move in a direction substantially at right angles to its first direction of movement.

In testimony whereof I have affixed my signature in presence of two witnesses.

GIUSEPPE MAZZOLINI.
